Primary Examiner — Derrick Holland*(74) Attorney, Agent, or Firm* — Michael Best & Friedrich LLP(57) **CLAIM**

I claim the ornamental design for a generator enclosure, as, shown and described.

DESCRIPTION

FIG. 1 is a front view of a generator enclosure.

FIG. 2 is a rear view of the generator enclosure shown in FIG. 1.

FIG. 3 is a right side view of the generator enclosure shown in FIG. 1, the left side view being a mirror image thereof. FIG. 4 is a top view of the generator enclosure shown in FIG. 1; and,

FIG. 5 is a front perspective view of the generator enclosure shown in FIG. 1.

The bottom view has no surface ornamentation and, therefore, has been omitted.

The broken lines shown represent unclaimed subject matter and form no part of the claimed design.
